UNITED STATES PATENT OFFICE.

SAMUEL GEISMAN, OF NEW YORK, N. Y.

DESIGN FOR A COVER.

58,562.

Specification for Design.

Patented Aug. 2, 1921.

Application filed November 27, 1920. Serial No. 426,818. Term of patent 14 years.

To all whom it may concern:

Be it known that I, SAMUEL GEISMAN, a citizen of the United States, and resident of the city of New York, borough of Manhattan, in the county and State of New York, have invented a new, original, and ornamental Design for a Cover, of which the following is a specification, reference being had to the accompanying drawing, forming a part thereof.

The figure is a face view of a pillow cover, showing my new design.

I claim:

The ornamental design for a cover, as shown.

SAMUEL GEISMAN.
